HOIST

Reinhold A. Uecker, Ingar G. Rambo and David E. Beatty, Wauwatosa, and Fred H. Graser, Milwaukee, Wis.

Application May 9, 1938, Serial No. 206,808

13 Claims. (Cl. 212—61)

This invention relates to hoists and more particularly to a hoist for use with scaffolds.

In construction and maintenance work employing scaffolds no satisfactory hoist has been devised for raising fairly heavy loads. In stone work, in particular, it is not uncommon to have loads of four to five hundred pounds. Such loads cannot be raised by an ordinary goose-neck.

One object of the present invention is to devise a hoist suitable for relatively heavy loads which is readily adaptable to a scaffold.

Another object of the invention is to produce a hoist including a drum and reel which is adapted to raise a load on the exterior of the scaffold and swing it onto the top of the scaffold.

A further object is to produce a hoist for use on scaffolds, the hoist having a swinging arm in which the hoisting reel remains stationary during the swinging of the arm.

20 A further object is to produce a hoist for use on scaffolds which is readily portable from one position to another.

A further object is to produce a hoist for use on scaffolds which may be readily converted from 25 a motor drive to a manually operated hoist.

A further object of the invention is to produce a hoist for use on top of scaffolds which may be secured in place with a minimum amount of labor.

Another object of the invention is to produce a 30 hoist for use on scaffolds which can readily and safely either raise or lower relatively heavy loads.

A further object of the invention is to produce a hoist for use on scaffolds which will support a load at any desired elevation.

35 A further object is to produce a hoist for use on scaffolds which can be used in combination with a safety guard rail.

These and other objects of the invention, the nature of which will become apparent as the description progresses, are accomplished by means 40 of the hoist shown in the accompanying drawings and described hereinafter in the specification.

In the drawings:

Fig. 1 is a perspective view of a tubular scaffold 45 of the type shown and described in the United States patent to Reinhold A. Uecker, Serial No. 2,043,498, issued June 9, 1936, with a hoist, forming the subject matter of the present invention mounted thereon;

50 Fig. 2 is a side elevational view of the hoist together with one corner of the scaffold;

Fig. 3 is a cross-section on the line 3—3 of Fig.

2, looking in the direction of the arrows;

Fig. 4 is a cross-section on the line 4—4 of Fig. 55 3, and shows the retaining ratchet;

Fig. 5 is an end view of the lower end of the hoist, showing the connection to the scaffold; and

Fig. 6 is a cross-section on the line 6—6 of Fig. 2, looking in the direction of the arrows.

Referring to the drawings, in which like numerals designate like parts throughout the several views, and referring particularly to Fig. 1, the scaffold is shown as composed of a pair of end frames or rings, generally designated 10—10, joined by cross braces 11—11, which maintain 5 the rings in spaced parallel relationship. Each ring 10 may be superimposed on similar rings 12 which support the rings 10 from the ground. Each pair of rings 12—12 is connected by cross braces 13—13, similar to the cross braces 11, 15 which maintain the rings 12 in alignment with the rings 10 and in spaced parallel relationship. Coupling pins 14 join the lower end of the upper rings 10 with the upper ends of the lower rings 12.

Each of the rings or end frames 10—10 or 20 12—12 comprises a pair of vertical posts 15—15 connected by horizontal braces 16—16 which are adapted to support scaffold planking which forms a deck 17. Diagonal braces 18—18 join the horizontal braces 16—16 and form the end frames or 25 rings 10 and 12 into integral rigid units.

All of the above structure is in itself old, and is more fully described in the Uecker patent, supra.

If desired, the top section of the scaffold or 30 the deck 17 may be protected by a guard railing 19, which may extend on one or more sides of the deck.

The hoist, which is generally designated 25, is shown in perspective in Fig. 1, and is shown in detail in Figs. 2—6 inclusive. It comprises a standard 26 which is preferably tubular, having an extension 27 formed on the lower end. The extension 27 fits snugly within the tubular post 15 and forms a pivot about which the standard 26 35 may rotate.

The upper end of the standard is provided with a goose-neck 28 which bends away from the standard and terminates in a yoke 29 which supports a pulley 30. Supporting braces 31 and 32 reinforce the goose-neck and permit heavier loads 40 to be raised.

The standard 26 is braced by a supporting frame which comprises a pair of tubular members 33 and 36 which are connected to a ring 37 at their upper ends, and diverge to the top of the 50 deck 17.

The ring 37 is freely rotatable on the standard 26 and is held in position by a pair of rings 40—40 sweated or welded to the standard 26. The lower divergent ends of the tubular members 33 and 36 55

are joined by an angle iron 42, which is adapted to rest on the top of the deck 17 and be secured to the horizontal brace of the scaffold by a hook bolt 43. The angle iron 42 is connected to a ring 44 surrounding the standard 26 by a tie rod 45 which may be tubular, as shown, or other suitable shape. The ring 44 is held in its proper position by rings 46—46 sweated or welded to the standard 26. The standard 26 is thus freely rotatable relative to the rings 37 and 44.

A reel, generally designated 50, is mounted in a saddle 51 which is supported on the braces 35, 36. The reel 50 is carried on a shaft 52 so that the reel and shaft may turn together, the shaft 52 being mounted in bearings 53—53 in the saddle 51.

The shaft 52 has crank handles 55 on the opposite ends, outside the bearings 53—53 so that the reel can be wound or unwound by turning the shaft. One of the handles 55 may be made removable and replaced by a pulley 56, which may be driven by a motor or engine 58, shown dotted in Fig. 2.

The reel 50 has a brake drum 60 formed on one side thereof, which is engaged by a brake band 62 to stop or retard the descent of the load. The braking action is regulated by a lever 63 pivoted to the saddle 51.

A ratchet 65 is secured to the opposite side of the reel 50 from the brake and is engaged by a pawl 66, pivoted to the saddle 51 to prevent unreeling of the reel 50 and hold a load at any given elevation.

In order to enable the standard 26 to be turned readily to swing a load onto the top of the scaffold a ring 75 is fixed to the goose-neck 28. The ring 75 carries a pulley 76 pivotally mounted, which is adapted to guide the rope 77 between the pulley 38 and the reel 50. By making the support for the pulley 76 circular, the goose-neck may be rotated to swing the load onto the deck of the scaffold without any tendency of the load to swing out due to the weight.

The guard rails 19 may be fixed to the hoist 25 through rotatable brackets 80 mounted on the standard between rings 81—81.

Having thus described the invention it is realized that it is susceptible to various changes and modifications, and it is not therefore desired to limit the invention to the precise form herein shown and described but only by the scope of the appended claims.

The invention set forth in the foregoing specification is hereby claimed as follows:

1. In a scaffold having a vertical post, and a horizontal member adapted to carry a deck, a hoist comprising, a normally vertical standard, an extension on said standard engageable with said post to form the connection therebetween, a goose-neck formed on the upper end of said standard, a brace connected between said goose-neck and said standard, and a second brace rotatably receiving said standard above its connection with said first brace and attachable to said horizontal member to reinforce the hoist.

2. In a scaffold having a tubular post, a hoist comprising, a tubular standard, a tubular extension formed on the lower end of said standard engageable with said tubular post to support the standard from the post and permit the same to rotate about a vertical axis, a goose-neck formed on the upper end of said standard, a pulley carried by said goose-neck, and means carried by said standard and rotatable relative thereto to secure a guard rail.

3. In a scaffold having a vertical post, and a horizontal member connected thereto, a hoist comprising, a standard, an extension on the lower end of said standard engageable with said post to form a connection therebetween, a goose-neck formed on the upper end of said standard, a pulley carried by said goose-neck, a brace connected with said standard below said goose-neck, a second brace connected with said standard adjacent said extension, means joining said braces at the outer end thereof, and means releasably securing the outer ends of said braces to said horizontal member.

4. In a scaffold including a vertical post and a horizontal member fixed to said post and adapted to support scaffold planking, a hoist comprising, a standard, an extension on the lower end of said standard engageable with said post to form a connection therebetween, a goose-neck formed on the upper end of said standard, a pulley carried by said goose-neck, a first brace joining said standard with the outer end of said goose-neck, a second brace connected with said standard above the connection of the first named brace therewith, and means to join the lower end of said second brace with the horizontal member of said scaffold.

5. In a scaffold including a vertical post and a horizontal member fixed to said post and adapted to support scaffold planking, a hoist comprising, a standard, an extension on the lower end of said standard engageable with said post to form a connection therebetween, a goose-neck formed on the upper end of said standard, a pulley carried by said goose-neck, a supporting brace joining the standard with the outer end of the goose-neck to increase the load-bearing ability thereof, a pair of braces connected to said standard above the lower end of said supporting brace and diverging downwardly, a supporting member joining the lower divergent ends of the said pair of braces, and adapted to rest on the planking, and means to fasten the supporting member to the horizontal member.

6. In a scaffold including a vertical post and a horizontal member fixed to said post and adapted to support scaffold planking, a hoist comprising, a standard, an extension on the lower end of said standard engageable with said post to form a connection therebetween, a goose-neck formed on the upper end of said standard, a pulley carried by said goose-neck, a supporting brace joining the standard with the outer end of the goose-neck to increase the load-bearing ability thereof, a pair of braces connected to said standard above the lower end of said supporting brace and diverging downwardly, a supporting member joining the lower divergent ends of the said pair of braces, and adapted to rest on the planking, means joining the supporting member with said standard, and means to fasten the supporting member to the horizontal member.

7. In a scaffold having a vertical tubular post and a horizontal member connected with said post, a hoist comprising a standard, a tubular extension on the lower end of said standard engageable with said post to rotatably support the standard therefrom, a goose-neck formed on the upper end of said standard, a pulley carried by said goose-neck, a ring on said standard, means to secure said ring at a fixed elevation on said standard while permitting the standard to rotate freely therein, and an outwardly and downwardly sloping brace secured to said ring and at-

tachable to said horizontal member to reinforce said standard.

8. In a scaffold having a vertical tubular post and a horizontal member connected with said post, a hoist comprising a standard, a tubular extension on the lower end of said standard engageable with said post to rotatably support the standard therefrom, a goose-neck formed on the upper end of said standard, a pulley carried by said goose-neck, a ring on said standard, means to secure said ring at a fixed elevation on said standard while permitting the standard to rotate freely therein, an outwardly and downwardly sloping brace secured to said ring, and means to secure said brace to said horizontal member to reinforce said standard at a point spaced from the bottom of said standard.

9. In a scaffold having a vertical tubular post and a horizontal member connected with said post, a hoist comprising a standard, a tubular extension on the lower end of said standard engageable with said post to rotatably support the standard therefrom, a goose-neck formed on the upper end of said standard, a pulley carried by said goose-neck, a ring on said standard, means to secure said ring at a fixed elevation on said standard while permitting the standard to rotate freely therein, a pair of braces connected to said ring and diverging outwardly and downwardly, a horizontal brace connecting the lower outer ends of said braces and means to secure said horizontal brace to the said horizontal member to reinforce said standard.

10. In a scaffold having a vertical tubular post and a horizontal member joined to said post, a hoist comprising a standard, a tubular extension on the lower end of said standard engageable with the post to rotatably support the standard therefrom, a goose-neck formed on the upper end of said standard, a brace connected between said goose-neck and said standard, a pulley carried by said goose-neck, a ring on said standard above the connection with said brace, means to secure the ring at a fixed elevation on said standard while permitting the standard to rotate freely therein; and an outwardly and downwardly sloping brace secured to said ring and attachable to said horizontal member to reinforce said standard.

50 11. In a scaffold having a vertical tubular post and a horizontal member joined to said post, a hoist comprising a standard, a tubular extension on the lower end of said standard engageable with the post to rotatably support the standard therefrom, a goose-neck formed on the upper end of said standard, a brace connection between said goose-neck and said standard, a pulley carried by said goose-neck, a ring on said standard

above the connection with said brace, means to secure the ring at a fixed elevation on said standard while permitting the standard to rotate freely therein, a pair of braces connected to said ring and diverging outwardly and downwardly, a horizontal brace connecting the lower outer ends of said last named braces, and means to secure said horizontal brace to said horizontal member to reinforce said standard.

12. In a scaffold having a vertical tubular post and a horizontal member connected with said post, a hoist comprising a standard, a tubular extension on the lower end of said standard engageable with said post to rotatably support the standard therefrom, a goose-neck formed on the upper end of said standard, a pulley carried by said goose-neck, a ring on said standard, means to secure said ring at a fixed elevation on said standard while permitting the standard to rotate freely therein, a pair of braces connected to said ring and diverging outwardly and downwardly, a horizontal brace connecting the lower outer ends of said braces, means to secure said horizontal brace to the said horizontal member to reinforce said standard, a second ring on said standard, means to secure said second ring on said standard at a fixed elevation thereon while permitting the standard to rotate therein, and a brace connecting said second ring with said horizontal brace.

13. In a scaffold having a vertical tubular post and a horizontal member joined to said post, a hoist comprising a standard, a tubular extension on the lower end of said standard engageable with the post to rotatably support the standard therefrom, a goose-neck formed on the upper end of said standard, a brace connected between said goose-neck and said standard, a pulley carried by said goose-neck, a ring on said standard above the connection with said brace, means to secure the ring at a fixed elevation on said standard while permitting the standard to rotate freely therein, a pair of braces connected to said ring and diverging outwardly and downwardly, a horizontal brace connecting the lower outer ends of said last named braces, means to secure said horizontal brace to said horizontal member to reinforce said standard, a second ring on said standard, means to secure said second ring on said standard at a fixed elevation thereon while permitting the standard to rotate therein, and a brace connecting said second ring with said horizontal brace.
